UNITED STATES PATENT OFFICE.

FRANK L. COES, OF WORCESTER, MASSACHUSETTS, ASSIGNOR TO LORING COES & COMPANY, INCORPORATED, OF WORCESTER, MASSACHUSETTS, A CORPORATION OF MASSACHUSETTS.

WRENCH-HANDLE.

SPECIFICATION forming part of Letters Patent No. 691,243, dated January 14, 1902.

Application filed October 28, 1901. Serial No. 80,182. (No model.)

To all whom it may concern:

Be it known that I, FRANK L. COES, a citizen of the United States, residing at Worcester, in the county of Worcester and State of Massachusetts, have invented a new and useful Improvement in Wrench-Handles, of which the following, together with the accompanying drawings, is a specification sufficiently full, clear, and exact to enable persons skilled in the art to which this invention appertains to make and use the same.

My invention relates to the provision in a wrench-handle of projecting side lips or guard-flanges formed on the outer angles of the handle-frame approximately at its mid-length or portion of greatest diameter or width, said lips fitting upon the opposite edges of the wood scales or handle-plates, as more fully hereinafter explained, the objects being to afford a midway support for the sides of the attached plates and to prevent swelling, splitting, or crushing of the wood portion and also to render the handle more efficient, durable, and desirable. These objects I attain by the wrench-handle illustrated in the accompanying drawings, wherein—

Figure 1 is a side view of a wrench having a handle embodying my improvement and shown as with the wooden side plate or scale removed for the better illustration of the parts. Fig. 2 is an edge view of the wrench-handle. Fig. 3 represents a transverse section at line X X on Fig. 1. Fig. 4 is a view of the inner face of one of the wooden side plates, and Fig. 5 represents a longitudinal section of the handle-frame and illustrates a modification in the shape of the edge lips.

Referring to the drawings, A denotes the wrench-bar, having a flattened shank A', on which the handle is mounted. The handle-frame F comprises the usual collar F' and step f for supporting the jaw-adjusting screw C and opposite edge filling bars or ribs 3, that extend along the front and rear edges of the bar-shank to the end of the handle and externally conform to the curvature of the handle-grip outline, the two bars or ribs being integrally joined to each other at one or both sides by a web 4 transversely across the space

occupied by the parallel-edged bar-shank in 50 suitable manner, as heretofore employed.

According to my invention I provide upon the edges of the handle-frame F, at a position about midway or approximately at the point of greatest diameter, opposite laterally-projecting oblong lips or guard-flanges 5, integrally formed upon both edges of the metal frame or edge filling-bars 3 at their outer angles, said lips standing out therefrom in the manner illustrated and embracing the edges 60 of the wooden side plates or scales H, in which latter I form recesses 7, into which said lips or guards 5 are received and fit when the parts are assembled, as best shown in Figs. 2 and 3. The length of said standing lips 5 is 65 preferably about one-fourth, more or less, of the length of the handle-plate or of such length as desired for various dimensions of handles, and the height of the lip is made such as will conveniently come within the 70 curve of the exterior surface.

The inner face of the handle-plate H is grooved or chambered at 8 to fit over the bridging-web 4 and formed with flat surfaces 9 along the border for seating firmly upon the 75 sides of the filling-bars 3 of the frame.

The inner faces of the guard-lips 5 seat against the sides of the wood and closely confine the plates H against transverse displacement, swelling, or splitting of the wood and 80 also against the crushing outward of the side plates. The outer surfaces of the lips are dressed off and finished flush and smooth with the exterior of the handle-frame and handle-plates.

The outline shape of the lips 5 is oblong and 85 preferably rounding, as shown in Fig. 2; but, if desired, they can be made square or rectangular, as in Fig. 5, or of desired contour at their edges which fit into the wood.

The ends of the handle-plates are formed with tenons 10 and 11 to fit under the rims of the collar F' and tip-piece G in well-known manner, and the usual bolt or rivet I is passed through the parts for securing the plates flatwise upon the handle-frame.

The handle-plate is assembled by introducing by the tenon 10 endwise beneath the rim

of the collar, then inserting the recessed part of plate flatwise between the two outstanding integral lips to bring its inner surface to seating position upon the frame, the tip-piece 5 G being subsequently passed over to the end of the bar-shank A'.

The standing lips 5 being located at the outer bulge of the handle or at the part that naturally comes in contact with objects in 10 the promiscuous disposal of the wrench in use they serve to prevent the chipping off of the thin edges of the wood at the wider parts, and thus preserve the handle in better condition than might otherwise ensue.

15 What I claim, and desire to secure by Letters Patent, is—

1. The metal wrench-handle frame, comprising a collar portion with a circular rim, longitudinal edge filling-ribs inclosing a bar- 20 receiving space that extends through the handle, and a web or webs integrally uniting said ribs along the bar-receiving space, said frame provided at the position of its greatest diameter, with opposite standing lips or flanges integrally formed upon both edges of the frame 25 and adapted to receive the handle-plate flatwise inserted between them; in combination, with the wrench-barshank extending through

the handle, the attached handle-plates having end tenons and edge recesses corresponding with said lips, said handle-plate chambered for flatwise assemblage over said uniting-webs and seating on the frame, a cupped end or tip piece fixed on the bar-shank, and means securing the opposite handle-plates on 30 the frame, all substantially as set forth.

2. In a wrench - handle, the combination with the metal handle-frame, comprising the edge filling-ribs united by side webs that extend longitudinally of the handle, and the 40 wood scales or handle-plates chambered at their inner faces and seated upon the sides of said frame; of the standing lips or guard-flanges integrally formed upon and projecting from the opposite outer angles at both 45 sides of said handle-frame, and embracing the edges of the handle-plates at a position intermediate to the ends thereof, for the purposes set forth.

Witness my hand this 26th day of October, 50 1901.

FRANK L. COES.
